X-RAY APPARATUS

Montford Morrison, Rochester, N. Y.

Application August 13, 1957, Serial No. 677,861

6 Claims. (Cl. 250—94)

The present invention relates generally to systems and methods for providing stabilization of voltages across a load in alternating current circuits, it relates more particularly to such systems and methods that employ electron discharge structures as a voltage stabilization means, and more specifically to such systems and methods that employ X-ray tubes in the load circuit.

Among the objects of this invention are: to provide a system and method which operates to stabilize the voltage across an X-ray tube by causing the X-ray tube voltage itself to control the stabilization; to provide an X-ray tube transformer load which balances the load on the X-ray tube transformer, making a symmetrically loaded system with the resultant symmetrical wave forms of voltage and current in the system which permits of greater simplicity and much more dependable structures in the control circuits; to provide a novel feed-back circuit from the load voltage to the transformer control circuit, in which X-ray tube filament transformers are formed to operate in the second role of feed-back capacitors, thereby not only eliminating the capacitance load on the X-ray tube transformer which would be imposed thereon by separate feed-back capacitors, but also eliminating the necessity of separate feed-back capacitors altogether.

The present invention, although it is disclosed as an X-ray structure and method, obviously it may be embodied in any equivalent structure and in any equivalent method.

In the prior art of self-rectifying X-ray tube operating apparatus, the resultant wave forms of voltages and currents are so distorted by the unbalanced load due to the X-ray tube, that stabilization of the tube voltage by circuit control has never been accomplished to any noteworthy degree. The difficulties encountered in such art are set forth to some extent in the applicant's Patent Number 2,495,122, issued January 17, 1950.

The specific nature of this invention, as related to X-ray tube operation, resides importantly in the art of self-rectifying X-ray tube operation where half-wave operation on the X-ray tube transformer unbalances all the connected circuits and the present invention not only balances the connected circuits, but definitely stabilizes them in this balanced condition by primary control from the X-ray tube voltage itself.

In the art of noncontacting thickness gauges, where X-ray radiation is employed as a means of determining the thickness of a material under measurement, the problem of stabilization of the X-ray tube voltage to a high degree of constancy is an all-important factor in the accurate determination of the thickness measured.

In the above-mentioned art, the conventional circuit employed is that of one self-rectifying X-ray tube imposed as a load on the secondary of a step-up alternating current transformer.

In the referred-to gauge art, two X-ray tubes may be employed to an advantage since two focal spot sources of X-rays are not a disadvantage and the double energy is an advantage because of the double signal energy to

2

the noise energy ratio attained in the amplifiers employed in the measurement of the X-ray energy used to determine the thickness measured in such gauges.

The various features and advantages of this invention will appear from the detailed description and claims when taken with the drawings in which:

Fig. 1 is a circuit illustrating one embodiment of the invention,

Fig. 2 is a circuit illustrating a second embodiment of the invention, and

Figs. 3 and 4 are end and side elevations, respectively, of a novel ancillary structure employed in the embodiments illustrated herein and which comprises an X-ray tube filament transformer having a feed-back capacitor structure formed in it.

In the circuit diagram of Fig. 1, 1 is a source of alternating voltage, 2 is a step-up X-ray tube transformer having center tapped primary 3, and a center tapped secondary 4, which may be grounded as illustrated, if and when desirable.

Further, 5 and 6 are grid or otherwise electrode controlled electron discharge structures which may be included in the same envelope, if and when desirable, but are illustrated as two separate triodes, however the number of electrodes employed in separate envelopes or in a single envelope is not a critical limitation, so long as each structure has at least one control electrode, which is referred to hereunder as a grid.

Structures 5 and 6, hereinafter referred to as triodes 5 and 6, have respectively a plate 7, a grid 8, a cathode 9, and a plate 10, a grid 11, and a cathode 12.

Alternating voltage source 1 is connected to the center tap 13 of transformer primary 3 and at point 14 to a cathode bias resistor 15 and through this resistor to the grounded triode lead 16. The triodes are thusly connected in the conventional push-pull manner including the primary of the transformer 2, but with an alternating voltage plate supply.

Transformer secondary 4 is connected by leads 17 and 18 to X-ray tubes 19 and 20. X-ray tubes 19 and 20 are connected to leads 17 and 18 in opposite conductivity relation so that the two X-ray tubes jointly provide an uninterrupted resistive load to the voltage of secondary 4, or one might describe the load as one of full wave rectification with high resistance rectifiers. It will be obvious to those skilled in the art to which the invention appertains, that the two X-ray tubes thus connected, have a load-equivalent in any nondirectional circuit resistance. It is further obvious that the invention is independent of whether the X-ray radiation from both X-ray tubes is used, or even from one alone.

Dotted areas A and B contain symbolic elements of an X-ray tube filament transformer, to be described in greater detail hereinafter. For the purpose of fully understanding the operation of Fig. 1, the details of the filament transformer shown in the area A will be identified, it being understood that the similar details of the filament transformer shown in area B are equivalents of those described. Referring to Fig. 1, 21 is a primary winding which may be connected, as conventionally indicated, to a suitable source of alternating current, 22 is a laminated steel core which may be grounded as indicated, 23 is one "plate" of a structure forming a capacitor, it being insulated from ground and from the high-voltage circuit 17, 25 is the transformer secondary which has an electrostatic shield 24 connected to it which forms the other "plate" of the capacitor stated, which will be referred to as capacitor 23—24. The similar capacitor of the filament transformer shown in area B, will be referred to as capacitor 26—27. In Fig. 1, 28 is a step-down transformer having a center tapped high-voltage primary winding 29, which obtains feed-back energy

from X-ray tube voltage leads 17 and 18, by means of capacitor 23—24 and capacitor 26—27. The center tap of the winding may be grounded as shown, if and when desirable.

The secondary 30 of transformer 28, is shunted by 5 capacitor 31, and the terminals of secondary 30 are connected to grids 8 and 11, as shown, in the conventional manner.

The generalized functioning of the structure shown in Fig. 1, can be stated in conventional terms, as will be 10 given hereunder, but the detailed operation cannot be stated correctly without employing the theory of such circuits which is only correctly set forth in the applicant's Patent Number 2,587,750 issued March 4, 1952.

In conventional terms, it can be stated that the stabilization of the X-ray tube voltage in the circuit shown in Fig. 1, is attained by feeding back the voltage across the X-ray tubes to the grids of the push-pull triodes through conventional circuit components having predetermined parameters and fixed circuit alignments, with 15 which an increase in X-ray tube voltage causes an increase in negative potential applied to the grids of the push-pull triodes, also in a reversed algebraic sense when the voltage decreases. Since the triodes may have a considerable amplification factor, small variations in X-ray tube voltages produce amplified effects in transformer 2. With the proper circuit parameters and proper 20 circuit alignments, a stabilization point may be reached where the degree of constancy of the X-ray tube voltage is largely inversely proportional to the amplification factor of the system.

Since the applicant has found that the phase angles, between the grid voltages and the plate voltages in such a circuit as disclosed, are not described correctly and 25 stated correctly in the literature other than in his above-referred-to patent, reference is made thereto for an understanding of the terms used in the specification and claims hereof, that are not found elsewhere.

In determining the parameters and the alignments of the feed-back circuit comprising capacitor 23—24, capacitor 26—27, high-voltage primary winding 29, low-voltage 30 secondary winding 30 and its shunted capacitor 31, the proper grid operating voltage angle (see Patent 2,587,750 for definition and theory thereof) can be determined as 35 fully taught in that patent. With the grid operating voltage angle (g. o. v. a.) determined, the several circuit components identified by the numerals 23—24, 26—27, 29, 30 and 31, can have their values determined by well-known conventional methods, to cause the proper g. o. v. a. of the correct voltage amplitude for operation under 40 stabilization of the X-ray tube voltage.

It is believed that a repetition in this application of the theory set forth in the patent referred to above, would be 45 redundant.

Referring to Fig. 2, this diagrammatic drawing, with the exception of the grid circuit, is identical with Fig. 1, and therefore the elements of Fig. 2 that are identical with the corresponding elements of Fig. 1, will not have a repeated description here, and only the changed grid 50 circuit will be described and discussed.

Assuming familiarity with Fig. 1, Fig. 2 will be referred to and in which transformer secondary winding 30, is provided with a system of full-wave rectification employing rectifiers 32 and 33, having a load resistor 34, shunted by capacitor 35. The voltage developed across resistor 34 and capacitor 35, provides a negative bias for the push-pull grids. The amount of current from source 1 passed through the push-pull triodes and primary 3, is inversely proportional to the negative grid bias voltage, 55 in an amplified ratio.

When the voltage across the X-ray tubes 19 and 20, rises, the grid bias voltage rises, lowering the current flow through the transformer primary 3, also in a reversed algebraic sense when the voltage across the X-ray tubes 50

falls. This effect is, as stated above, largely inversely proportional to the amplification factor of the system.

Fig. 2 thus operates as does Fig. 1, so far as result is concerned, but has the advantage that the g. o. v. a. does not have to be reckoned with in the structure, as the grid control voltage in this case is substantially continuous and not sinusoidal as in the case of Fig. 1.

Referring to Figs. 1, 3 and 4, 22 is a cruciform sectioned laminated steel transformer core of the conventional so-called core type, 21 is the primary winding, 36 is an insulating bushing surrounding the primary winding, 23 is a longitudinally split metallic sleeve forming one "plate" of the feed-back capacitor which is completed by a second "plate" comprising a longitudinally split sleeve 24, mounted upon an insulating bushing 37. The sleeve 23 extends to the entire length of the core window. The secondary winding 25 of the transformer is wound on the "plate" 24, to which it is electrically connected, as shown in Figs. 1 and 2.

The above-described transformer is obviously the filament transformer of Figs. 1 and 2, which not only serves as a filament transformer but also as a feed-back capacitor between the X-ray tube voltage and the grid control circuits of the push-pull triodes. This combination structure of filament transformer and feed-back capacitor, not only effects a large saving over the employment of separate high-voltage (up to 300,000 volts) capacitors, but further reduces the capacity load on the X-ray tube transformer, which load would be present with separate feed-back capacitors, and since there is considerable inherent secondary to primary electrostatic capacity in X-ray tube filament transformers, this capacity has to be increased only slightly by some small amounts of added surface to the effective electrostatic contours of the primary and secondary windings.

It is obvious from inspection of Figs. 1 and 2, that the load circuits of transformer 2 are perfectly balanced with reference to the alternating current flow therein.

I claim:

1. In an X-ray apparatus including a source of alternating voltage connected to the primary of a step-up transformer having its secondary supplying electrical energy to two X-ray tubes connected in a parallel relation providing both directions of circuit-conductivity load on the transformer, a step-up transformer having a primary and a secondary, a source of alternating voltage, two electron discharge structures each having a control grid and said structures connected between said source and said primary limiting the flow of current from source to primary under control of said grid when energized, a balanced voltage load on said secondary including two X-ray tubes connected in a parallel relation providing both directions of electrical circuit conductivity, and a feed-back circuit receiving energy from a parallel connection with said two X-ray tubes and applying a portion of it to said control grids, whereby the current flow from said source to said transformer is under feed-back circuit control by the voltage applied to the two X-ray tubes.

2. In an X-ray apparatus including a source of alternating voltage connected to the primary of a step-up transformer having its secondary supplying electrical energy to two X-ray tubes connected in a parallel relation providing both directions of circuit-conductivity load on the transformer, a step-up transformer having a primary and a secondary, a source of alternating voltage, two electron discharge structures each having a control grid and said structures connected between said source and said primary limiting the flow of current from source to primary under control of said grid when energized, a balanced voltage load on said secondary including two X-ray tubes connected in a parallel relation providing both directions of electrical circuit conductivity, a feed-back circuit receiving energy from a parallel connection with said two X-ray tubes and applying a portion of it to said control grids, said feed-back circuit including a step-down trans-

former with a capacitance loaded secondary connected to said control grids, and said capacitance loading in co-operation with coupled circuit inductance causing the correct grid operating voltage angle for said electron discharge structures under predetermined operation thereof, whereby the current flow from source to said transformer is under feed-back circuit control by the voltage applied to the two X-ray tubes.

3. In an apparatus including a source of alternating voltage connected to the primary of a step-up transformer having its secondary supplying electrical energy to two X-ray tubes connected in a parallel relation providing both directions of circuit-conductivity load on the transformer, a step-up transformer having a primary and a secondary, a source of alternating voltage, two electron discharge structures each having a control grid and said structures connected between said source and said primary limiting the flow of current from source to primary under control of said grid when energized, a balanced voltage load on said secondary including two X-ray tubes connected in a parallel relation providing both directions of electrical circuit conductivity, a feed-back circuit receiving energy from a parallel connection with said X-ray tubes and applying a portion of it to said control grids, and said feed-back circuit including a step-down transformer having a full-wave rectifier in the secondary thereof, the output of which is connected to the control grids of said electron discharge structures, whereby the current flow from source to said transformer is under feed-back circuit control by the voltage applied to the two X-ray tubes.

4. In an X-ray apparatus including a source of alternating voltage connected to the primary of a step-up transformer having its secondary supplying electrical energy to two X-ray tubes connected in a parallel relation providing both directions of circuit-conductivity load on the transformer, a step-up transformer having a primary and a secondary, a source of alternating voltage, two electron discharge structures each having a control grid and said structures connected between said source and said primary limiting the flow of current from source to primary under control of said grid when energized, a balanced voltage load on said secondary including two X-ray tubes connected in a parallel relation providing both directions of electrical circuit conductivity, a high-voltage-insulated filament transformer for each of said two X-ray tubes, a feed-back circuit receiving energy from a parallel connection with said two X-ray tubes and applying a portion of it to said control grids, and said feed-back circuit transmitting energy by means of the primary to secondary electrostatic capacity of said filament transformers, whereby the current flow from said source to said transformer is under feed-back circuit control by the voltage applied to the two X-ray tubes.

5. In an X-ray apparatus including a source of alternating voltage connected to the primary of a step-up transformer having its secondary supplying electrical energy to two X-ray tubes connected in a parallel relation providing both directions of circuit-conductivity load on

the transformer, a step-up transformer having a primary and a secondary, a source of alternating voltage, two electron discharge structures each having a control grid and said structures connected between said source and said primary limiting the flow of current from source to primary under control of said grid when energized, a balanced voltage load on said secondary including two X-ray tubes connected in a parallel relation providing both directions of electrical circuit conductivity, a high-voltage-insulated filament transformer for each of said two X-ray tubes, a feed-back circuit receiving energy from a parallel connection with said two X-ray tubes and applying a portion of it to said control grids, said feed-back circuit transmitting energy by means of the primary to secondary electrostatic capacity of said filament transformers and including a step-down transformer with a capacitance loaded secondary connected to said control grids, and said capacitance loading in co-operation with coupled circuit inductance causing the correct grid voltage operating angle for said electron discharge structures under predetermined operation thereof, whereby the current flow from said source to said transformer is under feed-back circuit control by the voltage applied to the two X-ray tubes.

6. In an X-ray apparatus including a source of alternating voltage connected to the primary of a step-up transformer having its secondary supplying electrical energy to two X-ray tubes connected in a parallel relation providing both directions of circuit-conductivity load on the transformer, a step-up transformer having a primary and a secondary, a source of alternating voltage, two electron discharge structures each having a control grid and said structures connected between said source and said primary limiting the flow of current from source to primary under control of said grid when energized, a balanced voltage load on said secondary including two X-ray tubes connected in a parallel relation providing both directions of electrical circuit conductivity, a high-voltage-insulated filament transformer for each of said two X-ray tubes, a feed-back circuit receiving energy from a parallel connection with said two X-ray tubes and applying a portion of it to said control grids, and said feed-back circuit transmitting energy by means of the primary to secondary electrostatic capacity of said filament transformers and including a step-down transformer having a full-wave rectifier in the secondary thereof, the output of which is connected to the control grids of said electron discharge structures, whereby the current flow from said source to said transformer is under feed-back circuit control by the voltage applied to the two X-ray tubes.
